CLAIM

(51) **LOC (10) Cl.** **26-02**

The ornamental design for a helmet-mounted light, as shown and described.

(52) **U.S. Cl.**

DESCRIPTION

USPC **D26/39**

FIG. 1 is a front elevational view of the helmet-mounted light;

(58) **Field of Classification Search**

FIG. 2 is a right-side elevational view thereof;

USPC D26/37-50; 362/171-174, 183-208

FIG. 3 is a left-side elevational view thereof;

CPC F21V 33/00; F21V 14/025; F21V 21/406;

FIG. 4 is a rear elevational view thereof;

      F21Y 2101/02; F21L 17/00; F21L 13/08

FIG. 5 is a bottom plan view thereof;

See application file for complete search history.

FIG. 6 is a front, bottom perspective view thereof; and,

(56) **References Cited**

FIG. 7 is a reference view showing the helmet-mounted light attached to helmet.
